UNITED STATES PATENT OFFICE.

CHARLES W. SLEEPER, OF LANCASTER, NEW HAMPSHIRE, ASSIGNOR TO
THE SLEEPER MACHINE COMPANY, OF MAINE.

CAN-CLEANING MACHINE.

SPECIFICATION forming part of Letters Patent No. 645,138, dated March 18, 1900.

Application filed November 15, 1899. Serial No. 737,043. (No model.)

To all whom it may concern:

Be it known that I, CHARLES W. SLEEPER, a subject of the Queen of Great Britain and Ireland, residing at Lancaster, in the county 5 of Coos and State of New Hampshire, have invented a new and useful Can-Cleaning Machine, of which the following is a specification.

In the process of packing meats and fish the cans become coated with an oily substance 10 which gives them a dirty appearance and interferes with the process of labeling by preventing the paste from adhering to the cans. Enameled or decorated cans cannot be washed in any fluid which would dissolve the oil, as 15 such fluid would destroy the decorations. The usual process of cleaning is to cover the cans with sawdust or other similar absorbent material and tumble them about in the sawdust until the oil is taken up. The cans are then 20 removed from the sawdust, which may be used over again until it becomes saturated with the oil.

The object of my invention is to provide suitable automatic mechanism for conducting 25 this process, such mechanism consisting, essentially, in means for tumbling the cans and the sawdust together in a cylinder, means for feeding the cans and the sawdust into the cylinder, means for separating the cleaned cans 30 from the sawdust, and means for returning the sawdust to the cylinder.

Figure 1 is a side elevation of my machine with a portion of the conveyer-trough broken away to show the chains and bars within. 35 Fig. 2 is a top view of the same with the cylinder C and a part of the can-conveyer A removed. Fig. 3 is a front view of same with the can-conveyer A removed and a portion of the elevator-box broken away to show the 40 elevator chain and buckets. Fig. 4 is a transverse section of the cylinder.

The can-conveyer A is composed of a trough, conveyer-chains, and driving mechanism, as follows:

45 a is a trough rectangular in cross-section, in the upper end of which is journaled the shaft a', carrying a drum a², upon the ends of which are sprockets engaging endless chains a³ a⁴, to which are secured a series of bars a⁴ 50 adapted to engage the cans to be cleaned. The chains a³ pass over sprocket-wheels a⁵ in

the lower end of trough a. Upon the shaft a' is a gear a⁶, which is engaged by a pinion (not shown) upon the shaft a⁷, upon which is a sprocket-wheel a⁸, driven by a chain a⁹, which is engaged by a sprocket-wheel a¹⁰ upon the main shaft a¹¹. The shaft a¹¹ is provided with a pulley a¹² to receive a suitable driving-belt. The conveyer A may be moved about the shaft a' to bring the trough a to any convenient position to receive the cans. 55

The sawdust-elevator B consists of the elevator boxes, chains, buckets, and driving mechanism, described as follows:

b b are two upright pipes or boxes rectangular in cross-section, connected at top and bottom by cross-sections of similar form, so as to form a continuous trough or elevator-box, the bottom section being open at the top and the top section being open at the bottom. 65

Four pairs of sprocket-wheels b¹ are arranged to carry a pair of endless chains b², (similar to chains a³), and between the chains b² are a series of elevator-buckets b³, arranged to take the sawdust from the bottom of the 70 elevator-box and drop it from the top of the box into a chute b⁴, which is hung between the upright boxes b b and enters the head of the cylinder C.

The elevator-chains are driven by sprocket-wheels upon the shaft b⁵, upon which is a bevel-gear b⁶, (see Figs. 1 and 2,), engaged by a pinion b⁷ upon the shaft b⁸, which carries a sprocket-wheel b⁹, engaged by the chain a⁹. 80

The cylinder C is composed of a shell c, 85 head c', rings c² c³, bars c⁴, and screen c⁵. The head c' partly closes one end of the shell c, leaving a circular opening about two-thirds the diameter of the shell, and c' is provided with a flange c⁶. The ring c² is provided with 90 gear-teeth and encircles the shell c. Bars c⁴ are attached to the inner surface of the shell c, parallel with its axis, and project a little more than one-half its length, the outer ends being secured to the ring c³. Between the rings c² and c³ a heavy wire screen c⁵ is wound over the bars c⁴, forming an extension of the shell c.

The cylinder C rests upon four rollers c⁷ upon the shafts c⁸ c⁹. A guide-roll c¹⁰ engages 100 the flange c⁶ to prevent the cylinder from sliding endwise upon the rolls.

The shaft c^8 carries a gear c^{11} , which engages the teeth upon the ring c^2 to rotate the cylinder.

A bevel-gear c^{12} , Figs. 1 and 3, upon the shaft c^8 is engaged by a bevel-pinion c^{13} upon the main shaft a^{11} .

The shafts c^8 c^9 and the guide-roll c^{10} are journaled in suitable hangers c^{14} c^{15} , which rest upon the frame of the machine.

10 A chute c^{16} is secured to the frame of the machine and arranged to receive the cans as they come from the cylinder C.

The sawdust-conveyer D is composed of a conveyer trough, chains, and driving mechanism described as follows:

15 d is a conveyer-trough, and d' d' are guide-rails placed above the trough d and connected with the same by heads in which are journaled the shafts d^2 d^3 , each of which carries two 20 sprocket-wheels d^4 . Two endless chains d^5 pass over the sprocket-wheels d^4 , and between the chains is secured a series of bars d^6 . The shaft d^8 carries a gear d^7 , engaged by a pinion d^8 upon a shaft d^9 , which carries a sprocket- 25 wheel d^{10} , engaged by a chain d^{11} , passing over a sprocket-wheel d^{12} upon the main shaft a^{11} . A hopper d^{13} is provided to guide the sawdust into the trough d .

30 In operation, the machine being in motion, a sufficient quantity of sawdust is put into the hopper d^{13} and carried by the conveyer D to the elevator B. The cans are placed upon the conveyer-chains in the trough of the conveyer A, which carries them up and drops 35 them into the chute b^4 . At the same time the elevator B drops a quantity of sawdust into the chute b^4 and upon the cans as they pass down the chute, and the cans and sawdust together enter the cylinder C, where they are 40 tumbled over and over by the bars c^4 as the cylinder revolves.

In consequence of the inclined position of the cylinder the cans move gradually downward and over the screen, the sawdust dropping 45 through the meshes of the screen into the hopper below to be used over again, while the cans pass out through the chute c^{16} into any convenient receptacle.

What I claim, and desire to secure by Letters Patent, is—

50 1. A machine for cleaning cans consisting of an inclined hollow cylinder terminating at its lower end in a screen, with means for rotating the same, means for feeding cans into the cylinder, means for feeding sawdust, or

other similar absorbent material, into said cylinder, and means for conveying such absorbent material after it has passed through the cylinder to said feeding mechanism last mentioned, substantially as described. 60

2. In a machine for cleaning cans an inclined hollow cylinder terminating at its lower end in a screen with means for rotating the same, in combination with a chute opening into the upper end of said cylinder, means for feeding the cans into said chute and means for feeding sawdust into the same, substantially as described. 65

3. In a machine for cleaning cans an inclined hollow cylinder terminating at its lower end in a screen, with means for rotating the same, in combination with means for removing the sawdust falling from the lower end of the cylinder and feeding the same into the upper end of the cylinder, substantially as 70 described.

4. In a machine for cleaning cans, in combination with an inclined hollow cylinder terminating at its lower end in a screen, with means for rotating the same, the sawdust-elevator B consisting of the elevator-trough b , b having its upper horizontal limb open on its lower side over the chute b^4 , endless elevator-chains b^2 , buckets b^3 , sprocket-wheels b' , chute b^4 , and means for operating said 75 chains, substantially as described.

5. In a machine for cleaning cans, in combination with an inclined hollow cylinder, terminating at its lower end in a screen, with means for rotating the same, the sawdust-conveyer D and elevator B consisting of the hopper d^{13} , conveyer-trough d , endless chains d^6 , bars d^6 , sprocket-wheels d^4 , elevator-trough b , b , endless elevator-chains b^2 , buckets b^3 , sprocket-wheels b' , chute b^4 , and means for 80 operating said conveyer-chains and elevator-chains, the several parts being so constructed and arranged with reference to each other that when in operation the sawdust dropping from the screen c^5 is carried by the conveyer 85 D into the elevator B and thence into the upper end of the cylinder C, substantially as described. 90

In testimony whereof I have signed my name to this specification in the presence of 105 two subscribing witnesses.

CHARLES W. SLEEPER.
